DRUM SUPPORT

Sam V. Cassato, Chicago, Ill.

Application October 25, 1946, Serial No. 705,513

2 Claims. (Cl. 84—421)

1

This invention relates to a new and improved supporting device for a bass drum and more particularly and specifically to a supporting device of a non-skidding construction.

The primary object of this invention is the provision of a unit adapted to be affixed to a bass drum which will form a non-rolling and secure support for the drum as well as a means for preventing the skidding or sliding of the drum.

Another object of this invention is the provision of a device of the character described which may be easily and quickly formed into a compact unit with the drum so that it may be packed and transported with the drum.

Another object of this invention is the provision of a device of the character described which is of a durable, simple and inexpensive design.

Still further improvements and advantages of this invention will readily appear to those skilled in the art when the following description is read in the light of the accompanying drawings in which:

Fig. 1 is a side elevation of the securing device with a drum and drummer's stool with the arms of the device in transporting position illustrated in dotted lines.

Fig. 2 is a top plan view of the device shown in Figure 1.

Fig. 3 is a vertical view of Fig. 1 taken on line 3—3 thereof.

Fig. 4 is a vertical cross section taken on the line 4—4 in Fig. 2.

Referring now to the accompanying drawings in which like numerals indicate similar parts throughout, the drawings which illustrate the securing device comprising a pair of horizontally placed legs A and B which are adapted to lie on the floor 1 in a desired spaced relationship. Positioned at similar places on each leg are two raised blocks 2 and 3 to which are secured horizontally hooked members 4 and 5. A second pair of blocks 6 and 7 of greater length than blocks 2 and 3 are secured to the end of each of the members A and B and are provided with a plurality of spaced holes 8 which are threaded to receive and securely fasten the bolt 9 which is affixed to a second pair of hooks 10 and 11, thus enabling the hooks to be selectively positioned relative to the first said hooks 4 and 5. This adjustable relationship between each pair of hooks adapts the members to securely fasten each outer rim of a bass drum on the blocks carried by the members A and B.

The inner ends of the members A and B are

2

hinged to a second pair of members or arms C and D which project outwardly and horizontally therefrom. Each of the second members C and D have a longitudinal slot 10 therein adapted to receive the set screws 11 and 12 which hold a cross bar 13 in place across the faces of members C and D. The cross bar 13 is similarly provided with slots 14 and 15 adjacent each end thereof in which the set screws 11 and 12 are secured. A cut out space 16 is provided in the center of the cross bar 13 adapting it to receive the foot 17 of a chair or stool leg 18.

The above described arrangement allows for the cross bar 13 to be slidably positioned and secured at any point longitudinally along the members C and D, thereby selectively positioning the bar 13 in relationship to the drum 19 which is secured transverse the members A and B. This arrangement also provides for the selective positioning of the members A and B longitudinally the cross bar 13 so as to adapt them to fit any desired bass drum, the selectively positioning means of the outside hooks 10 and 11 adapting the members A and B to selectively secure bass drums of varied width.

It can be seen that by the placement of the foot 17 of the leg 18 of a chair or stool 20 within the aperture 16 of the cross bar 13 that the weight of the occupant of the stool will, when the set screws 11 and 12 are tightened, prevent the sliding of the drum to or away from the occupant of the stool.

It can also be seen that when the stool 20 is removed from its engagement with the cross bar 13 that the members C and D, being hinged to the members A and B, may be vertically pivoted to an adjacent position to the drum, as illustrated at X in Fig. 1, so that the entire unit may be easily transported from place to place.

Having thus described and explained the construction and operation of this invention what I claim is:

1. In a device for supporting a drummer's stool and a drum having a rim disposed on its periphery adjacent each edge thereof, a pair of horizontally-disposed spaced parallel legs for the support thereon of said drum, clamping means on said legs for securing the drum in an upright position on said legs, said clamping means comprising a fixed block having a projecting hook on each of said legs for engaging the complementary rim of said drum, and a movable block having a hook projecting therefrom on each of said legs for engaging the opposite rim of said drum, a pair of longitudinally-extending arms each hav-

ing an end pivotally connected to one of said legs, a cross-bar arranged at right angles to said arms and mounted on the latter for slidable movement toward and away from said drum, said crossbar being arranged to support said stool intermediate said arms, and means for releasably securing said cross-bar in its adjusted position on said arms.

2. In a device for supporting a drummer's stool and a drum having a rim disposed on its periphery adjacent each edge thereof, a pair of horizontally-disposed spaced parallel legs for the support thereon of said drum, clamping means on said legs for securing the drum in an upright position on said legs, a pair of longitudinally-extending arms each having an end pivotally connected to one of said legs, a cross-bar arranged at right angles to said arms and mounted on the latter for slidable movement toward and away

from said drum, said crossbar being arranged to support said stool intermediate said arms, and means for releasably securing said cross-bar in adjusted position on said arms.

SAM V. CASSATO.
